UNITED STATES PATENT OFFICE.

GEORGE W. MAC KENZIE, OF BEAVER, PENNSYLVANIA.

DESIGN FOR A BADGE.

SPECIFICATION forming part of Design No. 26,233, dated October 27, 1896.

Application filed August 31, 1896. Serial No. 604,473. Term of patent 3½ years.

To all whom it may concern:

Be it known that I, GEORGE W. MAC KENZIE, a citizen of the United States, residing at Beaver, in the county of Beaver and State of Pennsylvania, have invented or discovered a new and original Design for Badges, of which the following is a full, clear, and exact description, reference being had to the accompanying drawings, forming part of this specification, in which—

Figure 1 is a face view of a badge made in accordance with my design. Fig. 2 is a cross-section therethrough on the line II II.

The leading feature of my design consists of a representation of a concentric row of sixteen grains of corn set or affixed upon a circular base or shield with a single grain in the center.

An additional feature consists in the contrasting color of the sixteen grains, which are made in a white or silver color, to the center grain, which is made of a yellow or gold tint,

the purpose of which contrasting coloration is to identify the grains with the two metals, silver and gold. The base 2 may also have 25 its face colored in any third contrasting color, as red.

For the purpose of securing the badge to the garment of the wearer a button 3 is provided, or a pin may be substituted.

The silver grains 4 and gold grain 5 are affixed, cemented, riveted, or made integral with the base 2 and are made in imitation of the grains of corn, or the natural grains may be used.

What I claim is—

The design for a badge as herein shown and described.

In testimony whereof I have hereunto set my hand this 19th day of August, 1896.

GEORGE W. MAC KENZIE.
